EXPANSIBLE LINK CHAIN FOR A BRACELET OR THE LIKE

Emil Rodriguez, New York, N. Y., assignor to
Jacoby-Bender, Inc., New York, N. Y., a corpora-
tion of New York

Application November 3, 1951, Serial No. 17,265

Term of patent 7 years

(Cl. D45—4)

To all whom it may concern:

Be it known that I, Emil Rodriguez, a citizen of the United States and a resident of New York, county and State of New York, have invented a new, original, and ornamental Design for an Expansible Link Chain for a Bracelet or the like, of which the following is a specification, reference being had to the accompanying drawing forming a part thereof, in which:

Fig. 1 is a top view of the expansible link chain in contracted condition showing my new design, portions of the conventional bottom links visible at the ends of the chain being shown in broken lines;

Fig. 2 is a top view thereof in partially expanded condition, portions of the conventional bottom links being visible between the top links and shown in broken lines;

Fig. 3 is a top plan view, on an enlarged scale, of one of the top links of the chain of Fig. 1;

Fig. 4 is a cross sectional view of the top link of Fig. 3 taken along the line 4—4 of Fig. 3;

Fig. 5 is a side elevational view of the top link of Fig. 3.

I claim:

The ornamental design for an expansible link chain for a bracelet or the like, as shown and described.

EMIL RODRIGUEZ.
